T. SCOTT ET AL

COMBINATION SHADE AND LAMP HOLDER

Filed June 18, 1921

UNITED STATES PATENT OFFICE.

THOMAS SCOTT AND FREDERICK K. MAERZ, OF CLEVELAND, OHIO.

COMBINATION SHADE AND LAMP HOLDER.

Application filed June 18, 1921. Serial No. 478,525.

To all whom it may concern:

Be it known that we, THOMAS SCOTT and FREDERICK K. MAERZ, citizens of the United States, residing at Cleveland, in the county 5 of Cuyahoga and State of Ohio, have invented a certain new and useful Improvement 10 in Combination Shade and Lamp Holders, of which the following is a full, clear, and exact description, reference being had to the accompanying drawings.

The purpose of our invention is to provide a combination lamp and shade holder for use in connection with electrical fixtures and which is adapted for the support of 15 the usual shade, with the electric lamp inside the same; or which, by reason of its design, may be used alone with the ball type electric lamp bulb and so harmonize with its shape as to produce an artistic and 20 finished effect, without omitting any of the parts or changing the holder in any way, to the end that a dealer in electrical goods may equip a fixture having our improved holders with either shades or ball lamps, ac- 25 cording to the aesthetic tastes of the customer, or the lighting requirements of the place wherein the fixture is to be used. The advantages of such a holder will be quickly recognized and thoroughly appreciated by 30 those familiar with the hardships heretofore experienced by dealers by their being unable to use either shades or ball lamps with a given fixture, for it has been the practice heretofore to make up fixtures for 35 use with one or the other but not with both. We speak, of course, of the higher class fixtures. Consequently, in the past, if a fixture of a certain design appealed to a customer and was equipped with shades, the dealer 40 would have to return the fixture to the manufacturer for the purpose of having it altered to adapt it to the ball lamp, or would have to order a new fixture fitted originally with ball lamps, and vice versa. 45 In general, our improved holder com- 50 prises a lamp socket, a skirt connected to the socket and flaring outwardly and downwardly from the open end thereof (assuming that the holder is in a pending position) and designed to receive the neck of the shade, and a flange which rises from the outer edge of the skirt and conceals (when the fixture is viewed at the usual angle) the securing means for attaching the 55 shade to the holder, the parts being so proportioned that when the shade is omitted

and a ball lamp is screwed into the socket, the skirt is in such close proximity to the bulb of the lamp as to practically close the open end of the skirt, concealing the parts 60 therein, and affording an attractive and finished appearance.

To the ends of economy and convenience, we prefer to include in the holder a shell 65 which encloses the usual lamp socket and from the lower edge of which the aforesaid skirt depends. This permits the use of stock sockets, so to speak, of standard shape and finish; while the holders which conceal the 70 sockets are made to harmonize in color, finish and design with the rest of the fixture.

In the accompanying drawing which constitutes a part hereof, Fig. 1 is a sectional side elevation of the present preferred embodiment of our invention, the holder being 75 shown as equipped with a shade and an ordinary electric lamp; Fig. 2 is a similar view of the same holder equipped with a ball lamp; and Fig. 3 shows a modification 80 of the invention having associated with it a ball lamp (in full lines) and a shade (in dotted lines).

The holder comprises a shell 1 that is closed at its upper end by a wall 2. The wall has a central aperture 3 through which 85 an extension of an external fitting 4 projects for connection with a lamp socket 5, situated inside the shell. A skirt 8 extends outwardly and downwardly from the lower end of the shell and joins, at its lower end, 90 an upwardly flaring flange 9. This flange preferably extends to such a height as to conceal, when the holder is viewed from the usual angle, the fastening means 10, arranged for holding engagement with the 95 grooved neck 11 of the shade 12. A lamp 13 is supported from the socket 5.

In Fig. 2 we have shown a ball lamp 15 associated with the holder, and when the 100 plug of the lamp is screwed into the socket 5, the bulb approaches very closely the lower edge of the skirt 8 and conceals from view the interior of the skirt and the inner ends of the fastening means 10.

In the modification illustrated in Fig. 3, 105 the holder comprises only the skirt 8^a, flange 9^a and holding means 10^a, the upper end of the skirt being directed inwardly at 20 and threaded for connection with the threads 21 of the socket 4. The present form has all 110 the advantages of the former embodiment except that the lamp socket is not concealed,

making it necessary, in this case, to finish the socket to correspond with the finish of the holder and fixture.

Having thus described our invention, 5 what we claim is:

1. In a device of the character set forth, the combination of a lamp socket, of a one piece shell enclosing and extending below said socket, the lower end of said shell being 10 enlarged and turned upwardly to define an ornamental ring, and globe attaching means carried by the enlarged portions of said shell and disposed below said socket, said shell being adapted to be used interchangeably with a lamp shade or with a ball type of lamp, and said enlarged portion of said shell being adapted to be closed by the bulb of a ball type of lamp when so used.
2. In a device of the character set forth,

the combination of a lamp socket, of a one 20 piece shell enclosing and extending below said socket, the lower end of said shell being enlarged and turned upwardly to define an ornamental ring, globe attaching means carried by the enlarged portion of said shell 25 and concealed by said upturned ring, said means being disposed below the end of said socket, said shell being adapted to be used interchangeably with a lamp shade and the usual type of lamp or with a ball type of 30 lamp alone, and when used with a ball type of lamp said ornamental ring being adapted to be in close proximity to the bulb of said lamp.

In testimony whereof, we hereunto affix 35 our signatures.

THOMAS SCOTT.
FREDERICK K. MAERZ.
